[57] CLAIM

The ornamental design for a fire detector, as shown and described.

DESCRIPTION

FIG. 1 is a perspective representation of a fire detector, illustrating my invention;

FIG. 2 is a front elevation of the fire detector of FIG. 1;
FIG. 3 is a rear elevation of the fire detector of FIG. 1;
FIG. 4 is a right-side elevation of the fire detector of
FIG. 1;

FIG. 5 is a left-side elevation of the fire detector of FIG.
1;

FIG. 6 is a top view of the fire detector of FIG. 1; and,
FIG. 7 is a bottom view of the fire detector of FIG. 1.

FIG. 1

FIG. 2

FIG. 3

FIG. 4

FIG. 5

FIG. 6

FIG. 7
